UNITED STATES PATENT OFFICE.

ROBERT NAYSMITH, OF PITTSBURG, PENNSYLVANIA, ASSIGNOR TO
PITTSBURG TUBE COMPANY, OF PITTSBURG, PENNSYLVANIA, A
CORPORATION OF PENNSYLVANIA.

SPRING-SUPPORT FOR BEDS.

No. 818,113.

Specification of Letters Patent.

Patented April 17, 1906.

Application filed October 2, 1905. Serial No. 280,983.

To all whom it may concern:

Be it known that I, ROBERT NAYSMITH, a citizen of the United States of America, residing at Pittsburg, in the county of Allegheny and State of Pennsylvania, have invented certain new and useful Improvements in Spring-Supports for Beds, of which the following is a specification, reference being had therein to the accompanying drawings.

This invention relates to certain new and useful improvements in spring-supports for beds; and the invention relates more particularly to a spring-support for folding iron beds.

The invention aims to provide positive and reliable means for holding a woven-wire fabric upon a frame which is connected to the head and foot pieces of a bed, whereby it can be elevated to permit of the head and foot of the bed being folded. To this end I have devised a novel form of casting which serves functionally as a universal joint between the spring-frame and the head and foot pieces of a bed.

In constructing my improved castings I have devised novel means for connecting the woven-wire fabric commonly used with such castings, said means embodying the frame, which adds rigidity and strength to a completed structure.

A further object of my invention is to provide a folding iron bed which will be extremely simple in construction, strong and durable, comparatively inexpensive, and highly efficient for the purposes for which it is intended.

With the above and other objects in view the invention finally consists in the novel construction, combination, and arrangement of parts to be hereinafter more fully described and then specifically pointed out in the claims, and referring to the drawings accompanying this application like numerals of reference designate corresponding parts throughout the several views, in which—

Figure 1 is a plan view of a bed constructed in accordance with my invention. Fig. 2 is a plan of the same folded. Fig. 3 is a detail perspective view of one of the rear corner-posts of the bed, illustrating my improved casting in connection therewith. Fig. 4 is a side elevation of another casting used in connection with my improved bed. Fig. 5 is a plan view of the same. Fig. 6 is an enlarged

detail front elevation of my improved casting, illustrating the same applied to the post 55 of a bed. Fig. 7 is a vertical sectional view of the same, taken on the line *x* *x* of Fig. 6, partly in elevation. Fig. 8 is a rear elevation of the same, and Fig. 9 is a side elevation of another casting used in connection with 60 my improved bed.

In the accompanying drawings I have illustrated a head-piece 1 and a foot-piece 2 of a conventional form of iron bedstead, these pieces constituting the four posts 5, 6, 7, and 65 8 of the bed. My invention resides in the spring-frame which connects these pieces together, forming a strong and rigid structure capable of being folded, whereby it will occupy comparatively small space.

In order that the bed may be folded, I employ special forms of castings which constitute my invention, and by referring to Figs. 6 to 8, inclusive, the main castings will be seen. In order that the bed may be folded 70 75 to occupy comparatively small space, I provide the posts 5 and 6 at the rear of the bed with special forms of castings, which serve functionally as universal joints, permitting the spring-frame 9 of the bed being folded 80 upwardly to a vertical position, as illustrated in Fig. 2 of the drawings, at which time the head and foot pieces 1 and 2 can be folded 85 inwardly against the vertical spring-frame 9. The castings which I use in connection with 85 the posts 5 and 6 and which will be herein-after called the "rear" castings are identical 90 in construction. Therefore I only deem it necessary to describe the special construction of the castings in connection with one post. 90 Each of the aforesaid rear castings consists of a two-part sleeve 10, which is adapted to be clamped upon one of the posts—for instance, the post 6. The two-part sleeve is provided with lugs 11 11, which are secured together 95 by nuts and bolts 12. The one part 14 of the casting is provided with an angularly-disposed lug 15, having a circular opening 16 formed therein. Mounted upon the lug 15 is a revoluble member 17, which consists of a 100 body portion 18, having a depending pin or stud 19, which is adapted to fit in the circular aperture 16 of the lug 15 and revolve therein at predetermined times. The body portion 18 of the revoluble member 17 is provided 105 with two upwardly-extending pierced flanges

20 20, which are adapted to receive the pierced depending lug 21 of a hinged corner-piece 22. A conventional form of nut and bolt 23 is then employed for pivotally connecting the corner-piece 22 to the revoluble member 17. The hinged corner-piece 22 consists of a body portion 24, the one side of which is provided with an angular extension 25, having an oval opening 26 formed therein. 5 The opposite face of the body portion 24 is provided with an outwardly-extending flange portion 27, which provides a groove 28 in the rear of the body portion 4. The top of the body portion 24 is provided with an upwardly-extending pin or stud 29, the object of which 10 will be presently described.

15 In connection with my improved bed I employ a conventional form of woven-wire fabric 30, and secured to the ends of this fabric are angle-bars 31 31. Metallic strips 32 32 are employed, together with rivets 33 33, for clamping the ends of the woven-wire fabric 30 to the angle-bars 31, this construction being specifically described in connection 20 with my accompanying applications. The ends of the angle-bars 31 and the strips 32 are provided with openings 34 34 to receive the upwardly-extending pin or stud 29 of each of the hinged corner-pieces.

25 30 In connection with the posts 7 and 8 at the front of the bed I employ castings herein-after termed the "front" castings, one of which is illustrated in Figs. 4 and 5 of the drawings. This casting consists of a two-part sleeve 35, having an outwardly-extending angular arm 36, which is slotted, as at 37, and this arm and slot forms a socket for the reception of a depending pin 38, carried by a casting 39, which is similar in construction to 35 the body portion 24 heretofore described, with the exception that the pierced depending lug thereof is dispensed with and the depending pin 38 substituted.

40 45 In assembling the different parts of my improved bed the sleeves 10 and the members 17 are placed upon their respective posts—namely, the posts 5 and 6 at the rear of the bed and the sleeves 35 are placed upon their respective posts 7 and 8 at the front of the bed. The hinged corner-pieces 22 are then pivotally connected by the bolts and nuts 23 to the members 17. The woven-wire fabric 30 having been connected to the angle-bars 31 31, these bars are placed in engagement 50 55 with the hinged corner-pieces 22 22 and castings 39 39. This operation is performed by passing the angle-bars downwardly upon the tops of the hinged corner-pieces and the castings, the vertical portions of the angle-bars 60 65 engaging in the grooves 28 of each casting, while the pins or studs 29 engage in the openings 34 34 of the angle-bars, rigidly holding the angle-bars in engagement with the corner pieces and castings.

65 65 In order to form a rigid framework for the

corner-pieces and castings which support the angle-bars and the woven-wire fabric, I employ front and rear rails 40 40, which are oval in cross-section, and these front and rear rails have their ends fitting snugly within the oval 70 openings 26 of the corner-pieces 22 and castings 39, and by the construction of the oval openings the side rails will be prevented from turning within the corner pieces and castings. The operation of placing the front and rear 75 rails between the corner pieces and castings causes the woven-wire fabric to become stretched, consequently forming a substantially rectangular frame which is adapted to be supported between the head and foot 80 pieces 1 and 2 of the bed.

When the different parts of my improved bed have been assembled, it will be observed that one side of the spring-frame is movably connected to the posts 5 and 6, while the opposite edge or side of the spring-frame simply rests upon the arms 36 36 of the sleeves 35 of the posts 7 and 8, the depending pins 38 of the castings 39 39 of the bed-spring engaging in the slots 37 37 of the arms 36 36. 85 In order that the bed-spring may be swung upwardly to the vertical position illustrated in Fig. 2 of the drawings, it has been necessary to provide the slots 37, which permit of the arc-like movement of the depending 90 pins 38 38 when the bed-spring frame is swung upwardly. The pivotal connection formed between the corner-pieces 22 and members 17 by the bolts 23 permit of the upward movement of the bed-spring frame. 95 After the frame has been so positioned the head and foot pieces 1 and 2 of the bed can be swung inwardly, as illustrated in Fig. 2 of the drawings, on account of the revoluble connection established between the members 17 17 and the sleeves 10 10 of the posts 5 and 6.

100 By the construction of my improved bed it will be observed that the same consists of comparatively few parts, to each of which 110 easy access may be had at any time it is desired to disassemble the bed—for instance, when it is desired to transport or ship the same. The novel form of castings which I employ permits of the bed being easily and 115 quickly folded.

120 What I claim, and desire to secure by Letters Patent, is—

1. In a folding bed, the combination with a head and foot piece, consisting of posts, of sleeves carried by said posts, angular arms carried by the front sleeves and having slots formed therein, front corner-castings, revoluble members carried by the rear sleeves, rear corner-pieces pivotally mounted upon 125 the revoluble members, an oval tubular side rail connecting the rear corner-pieces together and another oval tubular rail connecting the front corner-castings together, angular bars mounted upon the rear corner- 130

pieces and the front corner - castings, and adapted to support a woven - wire fabric, means to attach said fabric to said angular bars, substantially as described.

5 2. In a folding bed, the combination with a head-piece and a foot-piece consisting of posts, of sleeves carried by said posts, revoluble members connected to some of said sleeves, and corner-pieces hinged to said revoluble members, detachable castings connected to the other of said sleeves, tubular rails connecting said hinged corner-pieces together, tubular side rails connecting said detachable castings together, angular bars carried by said corner-pieces and said detachable castings, a woven - wire fabric carried by said bars, means to attach said sleeves to said posts, means to prevent the rails from rotating and means to detachably connect said bars to said corner pieces and castings.

10 3. In a folding bed the combination with a head and foot piece consisting of posts, of sleeves carried by said posts, angular arms carried by the front sleeves and having slots formed therein, front corner-castings engaging said angular arms, revoluble members carried by the rear sleeves, rear corner-pieces pivotally mounted upon the revoluble members, a side rail connecting the rear

corner-pieces together, another rail connecting the front corner-castings together, bars mounted on the rear corner-pieces and the front corner - castings and a woven - wire fabric attached to said bars, substantially as described.

35

4. In a bed, of the character described, the combination with a head-piece and a foot-piece, of a frame consisting of tubular front and rear rails, revoluble rear corner-pieces, detachable front castings and angle-bars connecting the rear revoluble corner-pieces with the front detachable castings, a woven-wire fabric carried by said angle-bars, means to detachably connect said fabric to said angle-bars, means to prevent the front and rear rails from rotating, means to pivotally connect the corner-pieces to the head and foot pieces, means to revolubly connect the corner-pieces to the head and foot pieces, and means to detachably connect the front castings to the head and foot pieces.

40 45 In testimony whereof I affix my signature in the presence of two witnesses.

ROBERT NAYSMITH.
